(57) **CLAIM**

The ornamental design for a wrist-worn physical activity measurement apparatus, as shown and described.

DESCRIPTION

FIG. 1 is a top perspective view of the wrist-worn physical activity measurement apparatus;

FIG. 2 is a bottom perspective view of the wrist-worn physical activity measurement apparatus;

FIG. 3 is a top view of the wrist-worn physical activity measurement apparatus;

FIG. 4 is a bottom view of the wrist-worn physical activity measurement apparatus;

FIG. 5 is a first end view of the wrist-worn physical activity measurement apparatus;

FIG. 6 is a second end view of the wrist-worn physical activity measurement apparatus;

FIG. 7 is a first side view of the wrist-worn physical activity measurement apparatus; and,

FIG. 8 is second side view of wrist-worn physical activity measurement apparatus.
